CLAIM

The ornamental design for an ultrasonic level meter, as shown and described.

DESCRIPTION

FIG. 1 illustrates a front view of a first embodiment of an ultrasonic level meter.

FIG. 2 illustrates a left side view of the ultrasonic level meter shown in FIG. 1.

FIG. 3 illustrates a top side view of the ultrasonic level meter shown in FIG. 1.

FIG. 4 illustrates a left side perspective view of the ultrasonic level meter shown in FIG. 1.

FIG. 5 illustrates a right perspective view of the ultrasonic level meter shown in FIG. 1; and,

FIG. 6 illustrates a right side rear perspective view of the ultrasonic level meter shown in FIG. 1.

The broken lines shown in the figures are for the purpose of illustrating portions of the ultrasonic level meter that form no part of the claimed design.
